UNITED STATES PATENT OFFICE.

WILLIAM R. FIELD, OF DECATUR, ILLINOIS.

APPARATUS FOR FEEDING PULVERIZED FUEL.

Application filed February 9, 1921. Serial No. 443,642.

To all whom it may concern:

Be it known that I, WILLIAM R. FIELD, a citizen of the United States, residing at Decatur, in the county of Macon and State of Illinois, have invented certain new and useful Improvements in Apparatus for Feeding Pulverized Fuel, of which the following is a specification.

This invention relates to apparatus for 10 burning pulverized fuel and particularly to improvements in apparatus for feeding the pulverized fuel.

Difficulties arise in feeding pulverized fuel to fuel burners because of the tendency 15 of the fuel, even when dry to pack in the storage tank, and because of its tendency to arch. This interferes with the regular and uniform feed of the fuel and causes either a diminution in the rate of feed or what 20 is known as flooding whenever an arch in the fuel breaks.

The invention has for an object to provide improved apparatus for feeding pulverized fuel which will be simple and inexpensive in 25 construction, and reliable in operation.

A further object is to provide apparatus of this character in which the feeding of the fuel will be regular and uniform and in which arching and flooding of the fuel will 30 be prevented.

A still further object is to provide a novel and improved means for varying the rate of feed of fuel.

The invention consists in the novel arrangements, constructions and combinations 35 to be hereinafter described and claimed, for carrying out the above stated object and such other objects as will appear from the following description.

The invention is illustrated in its preferred embodiment in the accompanying drawing, in which

Figure 1 is a perspective view of a storage vessel and the feeding apparatus.

Figure 2 is a vertical section thereof.

Figure 3 is a horizontal section taken on the line 3—3 of Fig. 2, and

Figure 4 is an enlarged detail view, being a vertical section showing the means for preventing leakage.

Like characters of reference designate like parts in the several figures of the drawing.

In the drawings, 10 designates a fuel storage or supply tank, supported on suitable supports 11 and preferably having at the bottom thereof a neck 12 of restricted cross-

section and preferably cylindrical in form. The bottom of the vessel is open, as indicated at 13, and the lower edge of the neck 12 is provided with a downwardly and inwardly inclined flange 14. Placed across the opening 13 is a horizontal revoluble disk 15 suitably supported by a vertical, revoluble shaft 16. The disk is provided with a central recess 17 for receiving the upper end of the shaft 16. The shaft and disk are connected rigidly together in any suitable manner, so that the latter may be rotated by the former.

Suitable mechanism for rotating the disk 15 at a proper speed is provided.

Arranged coaxially with the shaft and disk is a cone 18 having depending from the lower edge thereof a circular ring 19 which rests on the disk. The cone and ring are secured in place on the disk so as to rotate therewith by means of a bolt 20 which screws into a vertical hub 21 and clamps the cone and ring firmly in place, the hub 21 being preferably formed integrally with the housing of the recess 17.

The upper surface of the cone is provided with a plurality of ribs 22 which are preferably inclined in the direction of rotation of the disk. As illustrated, the disk is adapted to rotate in a clockwise direction.

A swinging feed gate 23 is provided in the side wall of the neck 12 adjacent the disk. This gate opens inwardly and extends into the annular space 24 formed by the ring 19 and the neck 12. In order to prevent leakage of fuel over the top of the gate, the latter is provided with a guard or cover 25 which contacts with the upper edge 26 of the gate opening 27. Preferably packing material 28 is provided along the upper edge 26 and contacting with the guard 25 to insure against leakage. The gate 23 is hinged along the vertical edge 29 so as to be adjustable and the cover 25 thereof is provided with a plurality of openings 30 into which a pin 31 may be inserted for securing the gate in adjusted position.

A wing or scraper 32 secured to the lower edge of the neck 12 and contacting with the rotating disk is provided for scraping or guiding off the fuel fed through the gate onto the outer margin 33 of the disk. The scraper is set at an angle to the direction of motion of the disk at that point so as to guide the fuel to the outer edge thereof. Suitable means, such as a chute 34, is provided for receiving the fuel from the disk and

for directing it to the fuel burner. The fuel may be carried to the burner in any desired manner, either by a current of air or some mechanical conveying means. Such means form, however, no part of the present invention. It is sufficient to note that any suitable conveying means may be employed with the feeding apparatus.

Operation.—Pulverized fuel may be placed to any desired level in the vessel 10. In the arrangement shown the disk is rotated at a uniform rate in a clockwise direction. The ribs 22 on the rotating cone serve to cut down the fuel into the annular space 24 so as to maintain a constant head at this point. The friction of the fuel on the disk rotates the fuel in the annular space 24 with the disk so that a portion thereof is discharged through the gate opening, depending upon the position of the forward edge 35 of the gate. If a greater rate of feed is desired, the gate is moved inwardly. The inclined flange 14 reduces the pressure or head of fuel on the disk adjacent the edge of the flange and prevents any substantial leakage of the fuel around the lower edge of the vessel. The ring 19 also prevents arching of the fuel between the inclined flange 14 and the cone. By maintaining the annular space 24 full of fuel both flooding and diminution in rate of feed are prevented.

It is not necessary to provide variable speed mechanism for rotating the disk. Any adjustment in the rate of feed of the fuel may be easily accomplished by adjustment of the gate.

I claim:

1. In apparatus of the class described, the combination of a storage vessel open at the bottom, a rotatable disk across said bottom, an adjustable feeding gate hinged to extend into said vessel adjacent said disk, and a laterally projecting guard on the top 45 of said gate for preventing leakage of fuel over the same.

2. In apparatus of the class described, the combination of a storage vessel open at the bottom, a rotatable disk across said bottom, an adjustable feeding gate in the side wall of said vessel adjacent said disk and extending into said vessel, a cover on the top of said gate and packing in said vessel across the top of said gate opening 55 and cooperating with said cover for preventing leakage of fuel over the top of said gate.

3. In apparatus of the class described, the combination of a storage vessel the bottom formed with an inwardly beveled flange 60 around its lower edge, and having a discharge opening in its side wall adjacent said lower edge, a horizontal, rotatable disk

across said bottom, means for rotating said disk and a feeding gate for opening and closing said discharge opening to control the 65 discharge of fuel.

4. In apparatus of the class described, the combination of a storage vessel having a feeding neck at the bottom thereof, said neck being open at its lower end and having 70 a downwardly inclined flange around said opening, a rotatable disk across said opening and extending beyond the sides of said neck, means for rotating said disk, a cone in said neck coaxial with said disk and having a 75 ring depending from the lower edge thereof and resting on said disk, means connecting said cone to said rotatable disk so that said cone and disk rotate together, ribs on said cone for cutting into the fuel in said vessel, a feeding gate in the side of said neck and extending into said vessel adjacent said ring, and means for adjusting said gate.

5. In apparatus of the class described, 85 the combination of a storage vessel having a feeding neck at the bottom thereof, said neck being open at its lower end and having a downwardly inclined flange around said opening, a rotatable disk across said opening and extending beyond the sides of said neck, means for rotating said disk, a cone in said neck coaxial with said disk and having a ring depending from the lower edge thereof and resting on said disk, means connecting said cone to said rotatable disk so that said cone and disk rotate together, ribs on said cone for cutting into the fuel in said vessel, a feeding gate in the side of said neck and extending into said vessel adjacent 90 said ring, and means for adjusting said gate. 95

6. In apparatus of the class described, 100 the combination of a storage vessel having a feeding neck at the bottom thereof, said neck being open at its lower end and having a downwardly inclined flange around said opening, a rotatable disk across said opening and extending beyond the sides of said neck, means for rotating said disk, a cone in said neck coaxial with said disk and having a ring depending from the lower edge thereof and resting on said disk, means connecting said cone to said rotatable disk so that said cone and disk rotate together, ribs on said cone for cutting into the fuel in said vessel, a feeding gate in the side of said neck and extending into said vessel adjacent 105 said ring, means for adjusting said gate, and means for removing the fuel discharged through said gate from said disk.

110

6. In apparatus of the class described, the combination of a storage vessel having a feeding neck at the bottom thereof, said neck being open at its lower end and having a downwardly inclined flange around said opening, a rotatable disk across said opening and extending beyond the sides of said neck, means for rotating said disk, a cone in said neck coaxial with said disk and having a ring depending from the lower edge thereof and resting on said disk, means connecting said cone to said rotatable disk so that said cone and disk rotate together, ribs on said cone for cutting into the fuel in said vessel, a feeding gate in the side of said neck and extending into said vessel adjacent 115 said ring, means for adjusting said gate, and a stationary scraper engaging the upper surface of said disk for removing the fuel fed through said gate.

WILLIAM R. FIELD.
